(71) Applicant: **PROFOTO AKTIEBOLAG,**
Sundbyberg (SE)

(72) Inventor: **Philip Fahlborg**, Nacka (SE)

(**) Term: **15 Years**

(21) Appl. No.: **35/504,659**

* cited by examiner

(22) Filed: **Sep. 18, 2017**

Primary Examiner — Holly E Thurman

(74) Attorney, Agent, or Firm — Cowan, Liebowitz &
Latman, P.C.

(80) **Hague Agreement Data**

(57) **CLAIM**

Int. Filing Date: **Sep. 18, 2017**

The ornamental design for a stand for photographic flash, as
shown and described.

Int. Reg. No.: **DM/099152**

Int. Reg. Date: **Sep. 18, 2017**

Int. Reg. Pub. Date: **Mar. 23, 2018**

(51) **LOC (12) Cl. 16-05**

DESCRIPTION

(52) **U.S. Cl.**

USPC **D16/237**

1. Stand for flash apparatus

1.1 : Perspective;

1.2 : Top;

1.3 : Right;

1.4 : Left;

1.5 : Front;

1.6 : Back.

(58) **Field of Classification Search**

Portions of the stand for photographic flash shown in broken
lines form no part of the claimed design.

USPC D16/134, 136, 200, 204, 208, 213–219,
D16/235, 237–250

CPC G02B 7/04

See application file for complete search history.
